UNITED STATES PATENT OFFICE.

WILLIAM ERASTUS WILLIAMS, OF CHICAGO, ILLINOIS.

PRESSED STEEL WHEEL.

1,392,380.

Specification of Letters Patent.

Patented Oct. 4, 1921.

Application filed September 6, 1919. Serial No. 322,168.

To all whom it may concern:

Be it known that I, WILLIAM ERASTUS WILLIAMS, a citizen of the United States, and a resident of Chicago, county of Cook, 5 and State of Illinois, have invented a new and useful Improvement in Pressed Steel Wheels, of which the following is a specification.

My invention relates to steel disk wheels 10 having special shaped corrugations and the objects of the invention are to provide a strong elastic disk and of a shape that will facilitate its fabrication into a wheel having general merits as described herein.

Reference will be had to the accompanying drawing in which—

Figure 1 is a front elevation of the wheel.
Fig. 2 is a diametrical section.

Fig. 3 is a perspective view of a section of 20 a serrated ring used in securing the brake drum to the wheel.

Fig. 4 is a plan detail showing how the disk is made.

In the drawing 1 indicates the axle of a 25 wheel and 2 the ordinary hub as found on an automobile but in this case adapted to suit my wheel, 3 indicates the common brake band drum fitted to my wheel, 4 indicates the regular demountable rim as commonly 30 used and secured in place by wedge clips 5.

My corrugated disk is indicated by 6 and it is formed from a straight strip of 35 steel approximately of a width equaling the length of the circumference of the wheel and it is formed into a disk shape by tapering corrugations as indicated in Fig. 4. The corrugations start from a smooth surface a short distance from the outside thus leaving a flat flange 7 on the rim which is 40 turned over laterally to form a sort of rim 8 for the disk.

The corrugations are deep enough at the hub side 9 to take up the edge 10 of the straight strip 11 and bring it around into 45 a circle forming a complete disk. The ends of the sheet after forming the disk are welded or otherwise suitably joined so that a complete circular disk is formed having as much metal on the hub circle edge as at 50 the rim edge thus arriving at a very substantial and efficient construction using the metal without waste and getting the full use of all of it.

In forming my disk the rear faces of the 55 salient corrugations are in a plane parallel to the general plane of the wheel and against

these faces rest the inner plane face of the brake drum. The annular main body of the disk is dished, its peripheral portion being carried toward the front of the wheel, and 60 through the peculiar dishing there is produced the angle 15 and the bulge 16 in the corrugations. This dishing has the effect of giving the disk a spring or elastic form in the matter of the thrust strains between 65 the hub and the rim thus producing an elastic wheel. Further by bringing the rim of the disk forward or toward the front it facilitates the fastening of the disk to the flange 13 of rim 14 as the rim 14 then can 70 be made of a simple strip in the same manner as common rims.

The disk is pressed into the rim 14 and there is provided a clamping ring 17 which 75 clamps the disk to the flange 13 of rim 14 by means of the rivets 18 or spot welds as desired.

The hub hole of the corrugated disk 6 is bushed by a casting 19 which is cast on the inner ends of the corrugations. Since the 80 disk is made of thin metal this cast on bushing usually welds fast to the disk sheet and in any case binds very tightly to the sheet and makes the disk very stiff at the hub. The casting 19 is machined to fit the hub 2 85 and is secured thereon by a screw threaded collar 20.

The brake drum 3 is offset at 21 to fit over the inner end of cast bushing 19. The rim of the drum is secured to the disk 6 by the 90 notched ring 22 riveted or spot welded at 23 to the drum 3. The notches 24 fit over the sides of the corrugations of the disk and flange ends 25 are secured by rivets or 95 spot welds to the front faces of the corrugations of the disk 6.

The metal of the disk 6 is quite thin and this notched ring 22 secures the brake drum 3 to the entire disk and at the same time it dams off the void spaces of the inside corrugations along the face of the brake band drum.

What I claim is:—

1. In a wheel of the class described, a disk having tapering corrugations extending radially deeper at the hub and shallower at the rim the back faces of the corrugations on the inside of the wheel adjacent to the hub being in a plane and the peripheral zone being dished outwardly from that plane. 105

2. In a wheel of the class described, a disk having tapering stiffening corrugations ex-

- tending radially and having in a plane the portions of their back faces which are adjacent to the hub, the peripheral zone of the disk being dished outward at the point 5 of connection to the rim of the wheel.
3. In a wheel of the class described, a continuous metal disk having tapering corrugations extending radially outward from the hub region to an annular non-corrugated 10 zone which is dished outward, with respect to a transverse plane passing perpendicularly through the free end of the axle, to a plane beyond the plane of the other parts of the disk, the outer part of said dished 15 portion forming an annular rim-receiving flange approximately perpendicular to the general plane of the wheel.
4. The combination with a wheel disk having tapered corrugations extending radially 20 from the hub region to an annular non-corrugated zone which is dished outwardly, its outer portion forming an approximately cylindrical rim-receiving flange of a hub-en- circling sleeve rigidly fixed to the corrugated central margin of the disk.
5. In a wheel of the class described, a disk having radial tapered corrugations extending from its central margin and surrounded by a non-corrugated peripheral zone dished 25 outwardly beyond the plane of other portions of the disk, the disk being provided at its central margin with a rigidly attached hub sleeve and at the dished zone with a reinforcing ring.
6. A wheel composed of a disk having 35 radially extending corrugations and dished across the corrugations thereby producing a radial spring construction.
7. In a wheel of the class described, the combination of a hub, a radially corrugated 40 disk, a brake drum fitting over the hub and against the disk corrugations, and a sleeve ring having one end portion fitting over and rigidly fixed to the drum and the opposite end portion notched to fit the contour of the 45 corrugation and rigidly fixed to the reentrant portions of the latter.
8. In a disk wheel having a radially corrugated disk, a straight inside back face for the corrugations adjacent to the brake 50 drum and the corrugations dished or bent outward from a line radially beyond the margin of the brake drum to the position of the flange on the front face of the rim.
9. A wheel of the class described having 55 a corrugated disk corrugated radially and with a bend or dish made transversely of the corrugations between their ends, thus changing the direction of the radial thrusts, with a rim on the periphery of the disk and 60 a hub at the center.

Signed at Chicago, in the county of Cook and State of Illinois, this third day of September, 1919.

WILLIAM ERASTUS WILLIAMS.
